UNITED STATES PATENT OFFICE.

CHARLES H. WAGNER, OF MILWAUKEE, WISCONSIN, ASSIGNOR TO L. J. MUELLER FURNACE COMPANY, OF MILWAUKEE, WISCONSIN, A CORPORATION OF WISCONSIN.

FURNACE STACK.

Application filed November 28, 1924. Serial No. 752,663.

This invention relates to improvements in furnace stacks more particularly adapted for conveying hot air from the furnace to the rooms to be heated.

5 In furnace installations the hot air pipes or stacks are usually formed in sections and the sections are assembled on the job by the workmen installing the heating plant. In assembling it is necessary to connect and disconnect the stack sections a number of times and it is desirable to provide a stack section joint which while holding the parts firmly together will permit the easy separation of the sections with the minimum effort.

15 A further object of the invention is to provide a furnace stack of the double wall type which is formed of but two pieces of metal.

It is one of the objects of the present invention to provide a furnace stack which will permit the joining of the sections together or the separation of the parts in a very simple manner.

25 A further object of the invention is to provide a furnace stack having a yielding locking means for locking two sections together and which means will permit the sections being easily separated.

30 A further object of the invention is to provide a furnace stack of the insulating double wall type which will permit a circulation of air through the double walls while forming a tight joint enclosing the hot air conduit.

35 A further object of the invention is to provide a furnace stack which is of simple construction, is strong and durable and is well adapted for the purpose described.

With the above and other objects in view the invention consists of the improved furnace stack and its parts and combinations as set forth in the claim, and all equivalents thereof.

In the accompanying drawing in which 45 the same reference characters indicate the same parts in all of the views:

Fig. 1 is a top view of the improved furnace stack;

Fig. 2 is a side view of two stack sections 50 connected together, portions being shown in section to illustrate interior construction; and

Fig. 3 is an end view of the parts shown in Fig. 2.

55 Referring to the drawing the numeral 5

indicates the outer wall and 6 the inner wall of the improved furnace stack which are bent at right angles transversely to form the inner hot air duct 7 and the surrounding insulating space 8. The inside wall 6 extends 60 upwardly in a straight line and its upper edge is overlapped by the channeled upper portion 9 of the outer wall 5. Said outer wall at its upper portion is bent outwardly and inwardly to form a stop rib 10 then upwardly a slight distance to provide an outer alining portion 11. The said wall is then angled inwardly upwardly and then abruptly outwardly to form a yielding locking shoulder 12 having a rounded outer edge portion 65 and the metal is then inclined upwardly inwardly to form a guide portion 13, and then continues upwardly to form the channel part 9 before mentioned. Said channel part 9 also forms an alining part 9' for the connected 70 section and is crimped diagonally as indicated by the numeral 9' to more firmly connect the channeled part and the upper edge of the inner wall together.

The lower portion of the inner wall 6 is 75 angled inwardly to form a stop rib 6' and then angled outwardly downwardly to the inner surface of the outer wall 5 to form the inner wall guide portion 14. The said portion then curves inwardly and then downwardly outwardly to the outer wall to form the fixed locking shoulder 15. The lower edge portion of the inner wall is then bent 80 downwardly in a straight line to form an inner wall alining portion 16 and then bent 85 outwardly upwardly to form a channel 17 which overlaps the lower edge of the outer wall 5 as clearly shown in Fig. 2. The lower angled portions just described are shaped to correspond to the angles of upper end of the 90 stack so that when two sections engage each other endwise, overlappingly the parts will closely fit each other and the shoulders will interlock and removably hold the parts together. Particular attention is directed to 95 the fact that the shouldered portion 12 is spaced from the inner wall 6 so that in connecting two sections together the said shouldered portion 12 can spring inwardly to pass the shoulder 15 and lockingly engage the same.

The upper opposite end portions of the outer part 5 from the shoulder 10 upwardly are beveled or angled towards each other at the corners as indicated by the numeral 18 100

to form openings 19 at the corners and to also freely permit the locking shoulder portion to yield inwardly when the parts are being disengaged or interlocked.

5 Said openings 19 while enclosed within the partly telescoped sections register with the corner openings 20 to permit the circulation of the insulating air through the registering openings but maintaining a closed passage-
10 way for the hot air within the inner wall 6.

The stop ribs 6' and 10 assist in holding the sections in alined position while the locking shoulders 12 and 15 firmly lock the sections together but permitting their easy
15 separation if desired.

While only one side wall formed of an inner and an outer wall has been described it is to be understood that the complete stack section includes four corresponding walls
20 forming a rectangular shaped conduit having an inner hot air passageway and a surrounding insulating air space.

From the foregoing description it will be seen that the yielding locking connection is
25 of very simple construction and well adapted for the purpose described.

What I claim as my invention is:

A furnace stack, comprising a stack section formed of inner and outer walls in
30 spaced relation, the upper portion of the outer wall being bent to form an outwardly projecting stop rib and then extending upwardly in a straight line to provide an

alinine portion and then extending inwardly upwardly and then outwardly in spaced relation to the inner wall to form a yielding locking shoulder extending approximately at right angles to the inwardly and upwardly extending portion, said locking shoulder being spaced from the inner wall, the said outer wall then extending upwardly at an angle towards the inner wall to form a guide portion, and then extending upwardly in a straight line to form an alining part and is then bent downwardly to form a channel into which the upper edge of the inner wall extends and is secured, the lower portion of the inner wall being bent inwardly to form a stop rib and then extending downwardly in a straight line for a short distance and then inclined downwardly outwardly to the outer wall to form a guide part and then bent inwardly approximately at right angles to the inclined portion and then is bent downwardly outwardly to form a non-yielding locking shoulder which contacts with the outer wall, the lower edge portion of said inner wall then extending downwardly in a straight line and then bent outwardly and upwardly to form a channel into which the lower edge of the outer wall extends and is secured, the corner portions of said stack section being open to permit the circulation of air through said openings.

In testimony whereof, I affix my signature.

CHARLES H. WAGNER.
